UNITED STATES PATENT OFFICE.

MOSES APPEL, OF BALTIMORE, MARYLAND.

ELECTRIC FURNACE.

1,013,359.

Specification of Letters Patent.

Patented Jan. 2, 1912.

Application filed September 9, 1911. Serial No. 648,426.

To all whom it may concern:

Be it known that I, MOSES APPEL, a citizen of the United States, residing at Baltimore, in the State of Maryland, have invented certain new and useful Improvements in Electric Furnaces, of which the following is a specification.

This invention relates to electric furnaces, the object of the invention being the provision of an efficient furnace of the resistance type adapted primarily for the refining of iron, steel, ferro-alloys and other metals, although capable of use for the production from their ores of iron, ferro-alloys, zinc and other metals. The furnace may also be used in the manufacture of glass.

The invention will be described by reference to the accompanying drawings illustrating one embodiment thereof, wherein:— Figure 1 is an end elevation of the furnace; Fig. 2 is a horizontal section on line 2—2 of Fig. 1; Fig. 3 is a transverse vertical section on line 3—3 of Fig. 2; and Fig. 4 is a vertical longitudinal section on line 4—4 of Fig. 3.

The furnace shown comprises a refractory furnace body 1, supported by a metal shell 2 and suitably mounted upon curved rails or beams 3 carried by a stationary support 4. These features of construction may conform to the approved practice in tilting open-hearth furnaces, the indications of the drawing being more or less diagrammatic in character.

The terminals or electrodes 5, 6 enter the ends of the furnace, and, for the manufacture of crucible or other high-grade steel, are preferably of metal of like character, being composed in this case of wrought iron or steel. Between the electrodes are disposed one or more main bodies or baths 7 of the metal to be refined. Three such baths are indicated, although a larger or smaller number may be provided. Each of these bodies is connected by a tap hole 8 with the spout 9, in such manner that the molten metal may be poured from these baths by tilting the furnace at a sufficient angle.

8' is a refractory plug.

The several main baths 7 are partly separated from each other by partial partitions 10 of highly refractory material, having provided therein open channels 11, which extend below the normal level 12 of the molten metal, in such manner as to provide interconnecting metal bodies of reduced cross-

section as compared with that of the main baths 7. As illustrated, the contracted channels 11 do not extend to the bottom of the molten bath, whereby the surface portions only of the main baths are in metallic connection. Similar partial partitions separate the end baths of the series from the electrodes 5, 6.

13, 13 represent cooling pipes for the circulation of water applied to the outer ends of the electrodes 5, 6. These electrodes are sufficiently cooled to guard against melting their outer ends, while the inner portions of the electrodes may be fluid in the normal operation of the furnace. In general, the portion of the electrode which extends through the furnace wall should be of as small cross-section as is consistent with the current to be carried, and should be operated at such temperature as will afford the best heat-economy, as is well understood in the art.

The protruding ends of the electrodes may be connected in an electrical circuit of any appropriate character and in any desired way. Thus a direct or alternating current of appropriate volume may be passed through the molten metal, or the construction may be adapted for use with a two- or three-phase current, or induced currents may be used. Thus as illustrated in Figs. 1 and 2, the terminals 5, 6 may be connected by a short, heavy copper lead 14, of sufficient cross-section to carry the current without undue heating, this lead traversing a primary coil 15, whereby the molten contents of the furnace and the lead 14, together with the electrodes, constitute a closed heating secondary circuit. As shown, the coil 15 is so carried upon the furnace body by brackets 16 with appropriate insulation 17 as to avoid interference with the tilting or pouring operation.

In operation, the furnace is charged with metal, usually in a melted state, and by passage of the current the metal is brought to the required temperature and so maintained for the required time, with the addition if desired of the usual reagents employed for the production of refined or alloy-steels. The heat is chiefly developed in the contracted passages between the main baths of metal and between these baths and the electrodes or terminal bodies 11 of metal, and is transferred largely by conduction, assisted by any natural circulation

or movement of the bath, to the main bodies of metal. In this manner it is practicable to bring the entire mass of metal to any desired temperature below the melting point of the lining of the contracted channels.

It will be noted that in the construction illustrated the contracted channels or passages 11 are located at one side of the center plane of the furnace. Owing to this construction, the cross-section of metal in these passages or channels varies with every position of the furnace; and conversely, the cross-section of metal in these channels, and hence its temperature under constant current conditions, and with it the temperature of the entire metal contents of the furnace, may be varied and controlled by merely tilting the furnace. Thus if the furnace be tilted in the direction of the solid arrow, Fig. 3, the effect will be to diminish the cross-sectional area of metal in each channel 11 and to increase correspondingly the heating effect of the current; while tilting in the direction of the broken arrow will have the contrary effect. In other words, the temperature of the furnace may be accurately controlled, regulated or varied, at the will of the operator, by tilting it forward or backward as conditions may require. Any arrangement or disposition of the channels to secure this result may be used.

The process as above described presents several important advantages:

(1) Although depending for the development of heat upon the resistance of the molten metal, it is very compact for a given capacity, whereby the radiation losses are minimized.

(2) The expense of carbon electrodes as well as the labor-cost of repairing and renewing such electrodes is avoided. At the same time all contamination of the bath by carbon is prevented, permitting the furnace to be employed for the manufacture of high-grade or crucible steels.

(3) The temperature of the furnace may be regulated with greater nicety and through a wider range than is the case with ordinary arc or resistance furnaces, by merely tilting the furnace, with or without the simultaneous control of the heating circuit. In case constant temperatures are required, a thermostatic control of the furnace temperature is easily provided, it being merely necessary that the position of the furnace should be automatically adjusted in accordance with the temperature indications.

(4) The furnace presents certain special advantages relating to the manufacture of steel. For instance, assuming the metal to have been poured into the furnace and refined to the required degree, the furnace may be slightly tilted in the proper direction for pouring, whereby the temperature is further increased, and the metal brought

to a highly fluid condition. At the same time, if desired, the flow of cooling water may be increased, in order to solidify all, or the principal portion, of the terminal masses 5, 6. Under these conditions the furnace may be discharged without loss of the material of the electrodes. By removing the plug 8' a branch circuit is established through taps 8, to maintain the proper fluidity of metal therein.

For the refining of non-ferrous metals the internal structure may remain as above described, the electrodes being constructed of such materials, as for example iron, carbon or copper, as may present advantages under particular conditions.

This furnace can also be used as a heating furnace for the production of various carbon and other compounds. The construction of the furnace would be the same as for the manufacture of steel, but the spaces occupied by steel would be occupied by iron, silica or other material which would act as a resister and also as a conductor of heat. It would be heated to high temperature as described under the refining of steel. The carbon or other material would then be added at the top of the molten resister and heated by conduction from it to any desired temperature. Any gases or other materials desired could be passed through the furnace and the various compounds made.

It is to be understood that the invention is not limited to the details of construction herein described by way of illustration, and that the form, size and proportion of the parts may be varied according to the character of material treated and the scale of operations.

I claim:

1. An electric resistance furnace mounted for oscillation and comprising a plurality of metal baths electrically interconnected at their surfaces, in combination with metallic electrodes in conductive relation with said baths.

2. An electric resistance furnace mounted for oscillation, said furnace comprising a plurality of metal baths electrically interconnected by relatively contracted channels, said channels so arranged that the cross-sectional area of conductor therein may be varied by tilting the furnace.

3. An electric resistance furnace mounted for oscillation and comprising oppositely disposed electrodes and a plurality of intermediate metal baths, said baths electrically interconnected at their surfaces by channels of relatively small cross-sectional area.

4. An electric resistance furnace mounted for oscillation and comprising oppositely disposed electrodes and a plurality of intermediate metal baths, said baths electrically interconnected by channels of relatively small cross-sectional area and so dis-

posed that the cross-sectional area of the conductors therein may be varied by tilting the furnace.

for oscillation and comprising a plurality of main baths of metal electrically interconnected at their surfaces, electrodes in conductive relation to the end baths, and a metal-
tap for each of said main baths. 15

In testimony whereof I affix my signature in presence of two witnesses.

MOSES APPEL.

Witnesses:

W. H. PAIRO,
HARRY B. KINGER.

5. An electric resistance furnace mounted for oscillation and comprising electrically interconnected metal baths, and electrodes in conductive contact therewith, a conductor connecting said electrodes to form a closed secondary circuit, and a primary winding
10 supported by the furnace in inductive relation to said secondary circuit.

6. An electric resistance furnace mounted
